FIG.2

FIG.1

FIG.3

FIG.5

FIG.4

FIG. 1 is a top plan view of a tablet dispenser showing our new design;

FIG. 2 is a view of the top of the tablet dispenser looking downwardly in FIG. 1;

FIG. 3 is a view of the side of the tablet dispenser looking to the left in FIG. 1;

FIG. 4 is a view of the bottom of the tablet dispenser looking upwardly in FIG. 1; and

FIG. 5 is a bottom plan view of the tablet dispenser design illustrated in FIG. 1.

The side of the tablet dispenser opposite that shown in FIG. 3 is substantially identical with that shown.

The essential features of the design reside in the full line portions, and the pills shown in broken lines are for illustrative purposes only.

We claim:

The ornamental design for a tablet dispenser, as shown and described.
